UNITED STATES PATENT OFFICE

2,150,407

BUCKLE

Paul W. White, Chicago, Ill., assignor to Parva Products Company, Chicago, Ill., a corporation of Delaware

Application August 10, 1936, Serial No. 95,053

7 Claims. (Cl. 24—194)

This invention relates to a slide buckle and has special reference to a device adapted to be mounted on belts, straps, and the like, for the support of garments or other objects particularly on the person, or for otherwise detachably securing articles together.

More particularly, this invention relates to a slide buckle comprising a pair of slidably engaged sheet metal frames in which one of the frames has 10 side bars and cross bars connecting the side bars with ledges secured to and spaced from the side bars to extend inwardly toward each other to form opposed channels when viewed in cross section, one of the cross bars presenting a strap-engaging face inclined relative to the plane of the frame and the other of the frames comprising 15 side bars engaging the opposed channels of the other frame to be guided in a longitudinal movement thereby. The cross bars connecting the side bars of the second mentioned frame form a strap-receiving slot, one of the cross bars thereof co-operating with the inclined face of the cross bar of the first mentioned frame to clamp a strap threaded therebetween and through the strap-receiving slot in desired adjusted positions.

The buckle of the present invention is adaptable for use with various types of objects particularly on the person and may be employed with slight variations not departing from the spirit of 30 the invention, universally where detachable connections are desired to be made. However, in the drawings and in the following description, the slide buckle is described and shown in its association with a belt, the belt being threaded between co-operating slidably engaged frames for 35 adjustably clamping the belt relative thereto. It will, of course, be readily apparent that various other uses may be made and that this invention is not to be limited to the specific uses herein described and illustrated.

Applicant contemplates the provision of a slide buckle formed of two slidably engaged sheet metal frames for the reception of the belt or strap threaded therebetween, the frame members co-45 operating to grip efficiently and at the same time to permit of a ready adjustment. The belt or strap is held positively against slipping after an initial application of tension without the necessity of providing sharp projecting prongs or other 50 like gripping members which mar or cut the material of the article gripped and is readily and conveniently drawn in either direction to adjust the same longitudinally therethrough with a maximum of ease. The sheet metal of 55 the frames is formed of very thin material, the

construction being so devised as to give the maximum strength necessary for durability with a minimum weight of material.

One of the objects of this invention is to provide a buckle comprising a pair of slidably engaged frames of the type hereinabove described in which a belt or strap threaded therethrough may be conveniently and easily adjusted in either direction.

A further object of this invention is to provide 10 a slide buckle comprising a pair of slidably engaged frames of the character indicated above in which the construction may be relatively inexpensive to manufacture, may be durable and simple in construction, and simple in threading 15 and manipulation.

Other objects and advantages will hereinafter be more particularly pointed out and for a more complete understanding of the characteristic features of this invention, reference may now be had 20 to the following description when taken together with the accompanying drawing, in which latter:

Figure 1 is a front elevational view of the buckle embodied in this invention in its relation 25 to a belt shown fragmentarily;

Fig. 2 is a view similar to Fig. 1 showing one end portion of the belt removed from the buckle;

Fig. 3 is a rear elevational view of the buckle, the belt in this instance not being shown;

Fig. 4 is a central longitudinal sectional view 30 taken on the line 4—4 of Fig. 2 showing one end of the belt threaded in an initial position in dotted lines ready to be clamped;

Fig. 5 is a view similar to Fig. 4 showing the belt in dotted lines in a clamped position; 35

Fig. 6 is a perspective view of one of the slidably engaged frames of the buckle of this invention;

Fig. 7 is a perspective view of the other slidably engaged frame of the buckle of this invention;

Fig. 8 is a view similar to Fig. 4 showing a modified form of buckle construction embodying the features of this invention; 40

Fig. 9 is a view similar to Fig. 6 of one of the slidably engaged frames of the buckle of Fig. 8; and 45

Fig. 10 is a view similar to Fig. 7 of the other of the slidably engaged frames.

Referring now to the drawing and more particularly to Figs. 1 to 7, inclusive thereof, the construction therein shown comprises a pair of frame members 10 and 11, the frame member 10 being preferably substantially rectangular in outline having side bars 12 and 13 connected by cross bars 14 and 15. The frame 11 is likewise preferably substantially rectangular in outline hav- 55

ing side bars 16 and 17 connected by cross bars 18 and 19 forming a slot 20. The side bars and cross bars of the frame 10 are preferably embossed or, in other words, the face of the frame 5 is raised providing a peripheral flange about the frame. This permits of the use of a minimum weight or gauge material to obtain a maximum rigidity.

The cross bar 15 of the frame 10 is preferably 10 of substantial width and presents a belt-engaging face 21 raised above the embossed portion thereof and inclined relative to the plane of the frame. The length of the belt-engaging face 21 is substantially greater than the distance between the 15 opposed inner edges of the side bars 12 and 13 so that a belt of maximum width threaded through the frame in engagement with the inclined face 21 will have the edges thereof rest against the faces of the side bars.

20 The frame 10 is provided with ledges 22 and 23 preferably formed integrally with the lower edges of the side bars 12 and 13, respectively, and extending inwardly toward each other to form opposed channels when viewed in cross section. 25 The channels receive the side bars 16 and 17 of the frame 11 and guide the frame in a longitudinal movement and in the direction of the plane of the frame, converging with respect to the inclined face 21.

30 The cross bars 18 and 19 are preferably of arcuate cross section having oppositely directed arcuate faces. The cross bar 18 of the frame 11 co-operates with the inclined face 21 of the frame 10 to clamp the belt 24 threaded therebetween 35 and through the belt-receiving slot 20 in various desired adjusted positions. By reason of the fact that the cross bars 18 and 19 are formed of arcuate cross section or are provided with arcuate faces, the engagement thereof with the belt will 40 produce no marring or cutting effect on the belt. Further, the provision of arcuate members of this type reinforces and strengthens the frame as a whole. The particular direction of the arcuate faces provides a preferable relation between 45 the belt and the frames 10 and 11 as is readily apparent from the drawing and particularly Figs. 4 and 5. The belt is shown as being turned in two directions, the directions of the turns of the belt being the same as the direction of the arcuate faces of the cross bars.

50 When it is desired to clamp the belt in an adjusted position, a tension on the belt 24 provides a relative longitudinal movement of the frame members 10 and 11 in opposite directions, the frame 10 being in a fixed position since it is 55 fixedly attached to one end of the belt and the other frame 11 having relative movement therewith since the belt is threaded through the belt-receiving slot 20 and is pulled in the direction 60 of the inclined face. The frame member 11 being directed in its movement in a plane parallel with the plane of the frame, the belt will be urged against the inclined belt-engaging face and the arcuate face of the cross bar 18. The 65 greater the tension on the belt, the firmer the belt is clamped between the engaging face of the co-operating cross bars because of the converging relation of the movable frames. The relation of the oppositely directed arcuate faces of 70 the cross bars 18 and 19 of the frame 11 and the inclined cross bar 21 of substantial width permits a gripping of the belt 24 without marring or cutting irrespective of the tension placed thereon. Thus, a desired clamping action is had without 75 sharp edges or teeth being employed.

Referring now more particularly to Figs. 8 to 10, inclusive, of the drawing, the embodiment of this invention therein shown comprises a pair of frame members 10a and 11a, the frame member 10a being preferably substantially rectangular in outline having side bars 12a and 13a connected by cross bars 14a and 15a. The frame 11a is likewise preferably substantially rectangular in outline having side bars 16a and 17a connected by cross bars 18a and 19a forming a slot 10 20a. The side bars and cross bars of the frame 10a are preferably embossed or, in other words, the face of the frame is raised providing a peripheral flange about the frame for the purpose of obtaining a maximum rigidity with the use of a 15 minimum weight or gauge material.

The cross bar 15a of the frame 10a is preferably of substantial width and presents a belt or strap engaging face 21a raised above the embossed portion thereof and inclined relative to 20 the plane of the frame. The buckle of this embodiment, as shown, is preferably for use with an ordinary strap such as may be employed on luggage, brief cases, skates, and the like, and the free edge 21b is rolled to permit the free 25 movement of a strap therearound as the free end portion of the strap extending from the buckle is pulled in a direction against that portion of the strap within and extending to the buckle, the rolled edge providing a fulcrum about which 30 the strap is bent.

The frame 10a is preferably provided with ledges 22a and 23a formed integrally with the lower edges of the side bars 12a and 13a, respectively, and extending inwardly toward each other 35 to form opposed channels when viewed in cross section. The channels receive the side bars 16a and 17a of the frame 11a and guide the frame in a longitudinal movement and in the direction of the plane of the frame, converging with respect to the inclined face 21a.

The cross bars 18a and 19a preferably present portions which are inclined with respect to the plane of the frame, the edge portion 18b of the cross bar 18a bounding one side of the slot 20a 4 being inclined in substantially the direction of the inclined face 21a of the frame 10a. The cross bar 18 of the previously described embodiment and present cross bar 18a may both be said to have portions which are turned out of 5 the normal flat plane of the frame, the function of both contemplating the provision of a strap-engaging portion which will effectively clamp the strap yet will not prevent a sharp clamping edge. The edge 19b of the cross bar 19a bounding the 5 other side of the slot 20a is turned out of the normal flat plane of the frame in a direction opposite to that of the inclined edge 18b.

By reason of the fact that the cross bars 18a and 19a are formed with oppositely directed inclined faces, or portions which are turned out of the normal flat plane of the frame, the engagement thereof with the belt will, in substantially the same manner as in the previous embodiment, produce no marring or cutting effect 6 on the belt. Further, the provision of these rolled or inclined edge reinforces and strengthens the frame as a whole. The belt or strap 24a is shown as being turned in two directions, the direction of the turn of the belt being the same as the direction of the inclined faces of the cross bars. Since the clamping of the belt in an adjusted position in the frame members of the buckle of this embodiment is the same as that previously 7 described in connection with the first mentioned

embodiment, a description thereof would merely be repetition and is deemed unnecessary.

While but two embodiments of this invention are herein shown and described, it is to be understood that various modifications thereof may be apparent to those skilled in the art without departing from the spirit and scope of his invention and, therefore, the same is only to be limited by the scope of the prior art and the appended claims.

I claim:

1. A slide buckle comprising a pair of slidably engaged sheet metal frames, one of said frames having embossed side bars and embossed cross bars connecting said side bars, ledges on said side bars extending inwardly toward each other to form opposed channels when viewed in cross section, one of said cross bars being of substantial width and presenting a strap-engaging face raised above the embossed portion thereof and inclined relative to the plane of said frame, and the other of said frames comprising side bars engaging said opposed channels of the first mentioned frame to be guided in a longitudinal movement thereby, and cross bars connecting said side bars for forming a strap-receiving slot, one of said cross bars co-operating with the inclined face of said first mentioned frame to clamp a strap threaded therebetween and through said strap-receiving slot in adjusted positions.

2. A slide buckle comprising a pair of slidably engaged sheet metal frames, one of said frames having embossed side bars and embossed cross bars connecting said side bars, ledges on said side bars extending inwardly toward each other to form opposed channels when viewed in cross section, one of said cross bars presenting a strap-engaging face inclined relative to the plane of said frame, and the other of said frames comprising side bars engaging said opposed channels of the first mentioned frame to be guided in a longitudinal movement thereby, and cross bars connecting said side bars for forming a strap-receiving slot, one of said cross bars having an arcuate face co-operating with the inclined face of said first mentioned frame to clamp a strap threaded therebetween and through said strap-receiving slot in adjusted positions.

3. A slide buckle comprising a pair of slidably engaged sheet metal frames, one of said frames having embossed side bars and embossed across bars connecting said side bars, ledges on said side bars extending inwardly toward each other to form opposed channels when viewed in cross section, one of said cross bars presenting a strap-engaging face inclined relative to the plane of said frame, and the other of said frames comprising side bars engaging said opposed channels of the first mentioned frame to be guided in a longitudinal movement thereby, and cross bars connecting said side bars for forming a strap-receiving slot, one of said cross bars having a portion inclined with respect to the plane of the frame and in the substantial direction of the inclined face of said first mentioned frame for co-operation therewith to clamp a strap threaded therebetween and through said strap-receiving slot in adjusted positions.

4. A slide buckle comprising a pair of slidably engaged frames disposed in a face-to-face substantially parallel relation, said frames having side bars and cross bars connecting said side bars for defining openings therethrough and receiving a strap threaded therebetween, means on said frames for directing relative longitudinal movements thereof, a cross bar on one of said frames presenting a strap-engaging face inclined relative to the plane of the frame, and a cross bar on the other of said frames being turned out of the normal flat plane of the frame for co-operation with the inclined face of the first mentioned frame to clamp the strap threaded therebetween in adjusted positions.

5. A slide buckle comprising a pair of slidably engaged frames disposed in a face-to-face substantially parallel relation, said frames having side bars and cross bars connecting said side bars for defining openings therethrough and receiving a strap threaded therebetween, means on said frames for directing relative longitudinal movements thereof, a cross bar on one of said frames presenting a strap-engaging face inclined relative to the plane of the frame, and a cross bar on the other of said frames having a portion inclined with respect to the plane of the frame and in the substantial direction of the inclined face of the first mentioned frame to clamp the strap threaded therebetween in adjusted positions.

6. A slide buckle comprising a pair of slidably engaged frames disposed in a face-to-face substantially parallel relation, said frames having side bars and cross bars connecting said side bars for defining openings therethrough and receiving a strap threaded therebetween, means on said frames for directing relative longitudinal movements thereof, a cross bar on one of said frames presenting a strap-engaging face inclined relative to the plane of the frame, and a cross bar on the other of said frames having a portion turned out of the normal flat plane of the frame in one direction and the other cross bar having a portion turned out of the normal flat plane of the frame in an opposite direction for co-operation with the inclined face of the first mentioned frame to clamp the strap threaded therebetween in adjusted positions.

7. A slide buckle comprising a pair of slidably engaged frames disposed in a face-to-face substantially parallel relation, said frames having side bars and cross bars connecting said side bars for defining openings therethrough and receiving a strap threaded therebetween, means on said frames for directing relative longitudinal movements thereof, a cross bar on one of said frames presenting a strap-engaging face inclined relative to the plane of the frame and having a rolled free edge, and a cross bar on the other of said frames being turned out of the normal flat plane of the frame for co-operation with the inclined face of the first mentioned frame to clamp the strap threaded therebetween in adjusted positions.

PAUL W. WHITE. 65
